VENTILATING FAN

Caryl A. Lindberg, Glendale, and Howard W. Eckles, St. Louis, Mo., assignors to The Emerson Electric Manufacturing Company, St. Louis, Mo., a corporation of Missouri

Application October 25, 1947, Serial No. 782,052

18 Claims. (Cl. 230—259)

1

The present invention relates to improvements in the construction of electric fans, particularly ventilating fans of the type wherein the air circulating blades revolve horizontally, the motor being mounted with its shaft in vertical position.

The principal object of the invention is to provide an improved ventilating fan which is sturdily constructed, light in weight and therefore readily portable, and which is adapted to circulate a maximum volume of air without creating the slightest semblance of a draft.

Another object is to provide a fan assembly wherein a novel baffle construction is adapted to diffuse the fan agitated air over an area of greater extent than that reached by conventional devices of this type.

Novel means are provided whereby assembly of the structural components is greatly facilitated.

Among the features of the invention is a motor-supporting bracket which may be quickly and easily removed should the motor need repairs.

The invention also consists in the construction and in the combinations and arrangements of parts described and claimed hereinafter.

Numerous additional features and advantages of the invention will be referred to in the description to follow, reference being had also to the drawings, in which the invention is illustrated.

In said drawings:

Fig. 1 is a front elevational view of the invention;

Fig. 2 is a bottom plan view thereof;

Fig. 3 is a horizontal sectional view thereof on the line 3—3 of Fig. 1;

Fig. 4 is a similar sectional view on the line 4—4 of Fig. 1;

Fig. 5 is a vertical sectional view substantially on the line 5—5 of Fig. 1;

Fig. 6 is a fragmentary view on an enlarged scale of the upper right hand portion of Fig. 5;

Fig. 7 is a similar view of the central and lower right hand portion of Fig. 5, some of the structure being broken away for clarity;

Fig. 8 is a horizontal sectional view on the line 8—8 of Fig. 6;

Fig. 9 is a similar view on the line 9—9 of Fig. 7;

Fig. 10 is a fragmentary sectional view of a housing support, illustrating structural details;

Fig. 11 is an elevational view of a guard cleat per se;

Fig. 12 is a similar view of the motor supporting bracket with a portion thereof in section; and

Fig. 13 is a front elevational view of the cir-

2

cular guard member which supports a baffle and top cover assembly of the invention.

With particular reference now to Figs. 1 to 5, inclusive, the ventilating fan of the present invention is generally indicated 20. It includes a circular housing designated 21, an annular bottom therefor generally designated 22, and supporting members or standards generally indicated 23.

10 The housing 21, as illustrated, is preferably constructed of expanded metal, but obviously it may consist of a rigid perforated structure of other design.

15 Preferably, the leg portions 24 of said supporting members are provided with rubber pads or bumper elements 25, as shown.

20 Centrally of and within the housing 21 is mounted an electric motor 26, which may be connected to a source of electrical energy by means of a cord 27 and plug 28. The motor is mounted, with its drive shaft 29 in vertical position, in a novel manner by means of a bracket member generally indicated 30, and shown per se in Fig. 12.

25 A fan blade assembly comprising blades 31 and a hub member 32, to which they are secured, is fastened to the projecting upper end of the shaft 29 by means of a setscrew 33, as shown in Fig. 5.

30 Secured adjacent the upper peripheral portion of the housing 21 in a manner to appear herein-after is a circular open guard member generally designated 34, and shown per se in Fig. 13. Supported by the guard member 34 in a manner to be described, is a baffle member generally designated 35, and a top cover plate generally indicated 36.

35 With particular reference now to Figs. 7, 9 and 10, it will be seen that each of the supports 23 is substantially channel-shaped in horizontal cross section and terminate in a closed rounded upper end 40 which impinges against an inverted V-shaped trim ring 41 which is clamped over the upper peripheral edge 42 of the housing 21.

36 From the top 40, the two side flanges 43 of each support 23 continue downwardly adjacent the housing 21, above the lower end 44 of which each flange 43 has formed therein a semi-circular notch 45 which receives a split trim ring 46. This trim ring is also in contact with the upper peripheral edge 41 of the bottom member 22 around its entire periphery.

40 As best seen in Fig. 10, each side flange 43, a short distance below the notch 45, is widened considerably to provide a substantial arcuate seat 48 for the bottom member 22, the annular marginal portion 49 of which is correspondingly arcuate. The six arcuate seats 48 thus provide

ample supporting means for the bottom member 22 to which, in a manner to be described, the motor supporting bracket 30 is removably secured.

In addition to the side flanges 43, each standard 23 includes an integral web portion 50 extending from top to bottom thereof, as illustrated. Vertically spaced upper and lower stud elements 51 and 52, each comprising shank portions 53 and head portions 54, are spot-welded as at 55 to the web 50 of each standard, as shown most clearly in Fig. 10.

The annular guard member 34 preferably includes an upper ring 60, a lower ring 62, and an intermediate ring 61. These rings are maintained in spaced parallel relation by being welded as at 63 to a plurality of uprights including single bars 64 and double bar elements generally designated 65.

In the embodiment of the invention illustrated, six single bars 64 and three double bar members 65 are provided. While a greater or lesser number of uprights may be employed, the selected quantity has been found adequate to support the baffle member 35 and the top cover 36 of the fan.

As shown especially in Fig. 13, the upper end 68 of each single bar 64 terminates a short distance above the ring 60, and the lower end 69 terminates a short distance below the lower ring 62. It is also seen that the upright bars 72 of each element 65 are connected at their upper ends by an integral horizontal cross bar 73.

Thus, each element 65 is of inverted U-shaped configuration, with its horizontal or bight portion 73 extending above the upper ends 68, and its vertical or leg portions 72 extending below the lower ends 69 of the single bars 64. As shown particularly in Fig. 3, the single bars 64 are arranged in pairs spaced apart a distance similar to that obtaining between the uprights 72 of each member 65. It is also seen that the double bar elements 65 alternate with the pairs of adjacent single bars 64, so that a symmetrical pattern is presented.

Approximately intermediate the lower ring 62 and the lower extremities 75 of each pair of legs 72, there is welded to said legs, as at 76, a rectangular plate 78 provided with a slightly elongated aperture 79. Three apertures 79 are thus provided, they occupying a position one hundred twenty degrees apart on a circle described from the center of the device.

Three similar apertures 80 are provided in the bottom cover 22 a short distance below the upper edge 47 thereof.

The manner in which the standards 23 are secured to and support the device will now be described. The standards 23 are three in number and are equally spaced one hundred twenty degrees apart. They are similar in all respects with one exception, that being the provision of a hole 82 in the front standard only.

As illustrated in Fig. 7, the purpose of this opening is to support the casing 83 of a manually operable three-speed switch of conventional design, as will appear. A suitable opening 84, to accommodate the switch casing, is provided in the housing 21 in line with the opening 82. The switch has a threaded projection 85 which passes through the hole 82 and receives a nut 86, which, when tightened, maintains the switch 83 in place on the standard. A washer may be interposed between the nut 86 and the web portion 50, or, as illustrated, an apertured name plate 87 may be so interposed.

A suitable knob may be secured to the projecting squared end 88 of the switch stem by means of the screw 89, or in any other well known manner. Thus, the speed of the motor may be manually regulated, as is understood. It is also evident that removal of the knob, by extracting the screw 89 followed by screwing off the nut 86, is all that is required to dismount the switch casing 83.

10 In the assembled device, as also shown particularly in Fig. 7, one of the three apertures 79 is in vertical alignment with one of the three apertures 80 in the bottom cover 22. Furthermore, the aperture 79 is in horizontal alignment with the stud 51. The latter passes through the perforated housing 21, thence through an elongated opening 90 in a relatively narrow vertical strip of metal 92, and thereafter through the aperture 79 to receive a speed nut 94.

15 The metallic strip 92, referred to above, is welded or otherwise secured to the housing 21 for the purpose of providing an opening 90 of a size and shape corresponding to that of the openings 79 and 80. Obviously, a strip 92 is secured to the housing 21 opposite each standard 23. Opposite the front standard, the upper edge of said strip abuts the lower edge of the trim ring 41 and extends downwardly until cut off, as at 93, because of the presence of the switch 83. The remaining two strips 92, one of which is depicted in Fig. 5, extend substantially from the trim ring 41 to the lower end 44 of the housing.

20 From the foregoing, it should be evident that an arrangement has been provided which admits of ready assembly or disassembly of the upper portion of the housing 21, the upper portion of each standard 23, and the lower portion of the guard member 34. As shown in Fig. 7, the lowermost ring 62 of the guard member rests upon the upper edge of the trim ring 41 which, as will later appear, facilitates the assembly operation.

25 With reference now to the lower right hand portion of Fig. 7 and Fig. 10, the standard 23 provides six seats 48 to receive the bottom 22, as has been previously explained.

30 Since the studs 51 and 52 of each standard as well as the apertures 79 and 80 are in vertical alignment, the stud 52 passes through the aperture 80 and thence through the lower portion of the housing to receive a speed nut 98.

35 Referring briefly to Fig. 5, it is noted that, where the strips 92 extend from top to bottom of the housing, the studs 52 also pass through an opening similar to the opening 90 previously referred to and for the same purpose. In other words, each of these two strips has a slightly elongated opening 90 therein adjacent its lower as well as its upper edge. It is thus seen that an arrangement has also been provided adapted

40 for ready assembly or disassembly of the lower portion of the housing 21, the lower intermediate portion of each standard 23, the bottom member 22, and the trim ring 46.

45 In order to diffuse the air agitated by the fan assembly, the baffle member 35 is mounted on and supported by the guard member 34 above and in spaced relation to the blades 31.

50 As illustrated in Figs. 1, 3, 5 and 6, the baffle member consists of a shell 102 of frusto-conical contour, merging into an annular arcuate portion 103, the latter terminating in an upstanding annular flange 104. At equally spaced intervals around its peripheral margin, the baffle has formed therein one of a series of six similar indentations or depressions 106 to accommodate

the upper ends 68 and 73, respectively, of the upright members 64 and 65.

As seen at the upper left in Fig. 5, the upper end 68 of each single bar 64 terminates flush with the top edge of the flange 104. The bight portion 73 of each double bar member 65, however, as seen in Fig. 6, extends above the upper edge of said flange, and rests upon the horizontal flange 108 of a guard cleat 109.

There are three guard cleats 109, one for each double bar member 65. In addition to the horizontal flange 108, each of these cleats includes a vertical flange 110 in contact with and extending across the pair of uprights 72 of each member 65, as clearly illustrated in Fig. 8.

Welded to the vertical flange 110 centrally of each cleat 109, as at 112, is the head portion of a stud element 114, the shank portion 115 of which is horizontally disposed.

In regard to the depressions 106, it is seen by reference to Figs. 6 and 8 that each includes a perpendicular wall 118 and side walls 119, all merging into the marginal periphery of the baffle member. As viewed in horizontal cross section, the corners 120 which join the perpendicular wall with the side walls are arcuate to snugly engage the upper ends of the uprights 72 or 64 of the guard member.

There is an aperture 122 in the wall 118 of each of those three depressions 106 which are in line with the standards 23. The shank 115 of a stud 114 passes through this aperture and receives a speed nut 124. An annular rounded groove or depression 126, interrupted only by the indentations 106, is also provided on the baffle member and receives the uppermost ring 60 of the guard member to facilitate assembly, as will appear later.

It should now be evident that there is provided an arrangement which admits of ready assembly and which maintains the baffle member 35 rigidly in position on the upper part of the guard member 24.

The cover 36 comprises a flat top portion 130 merging into an annular marginal portion 131, which fits over the annular flange 104 of the baffle member with its bottom peripheral edge 132 resting upon the ring 60 of the guard member, as illustrated in Fig. 6.

A plurality of U-shaped brackets 134, the legs 135 of which have laterally extending flanges 136, are welded, as at 137, or otherwise secured to the top 130. Four such brackets are provided in the device illustrated, they being spaced ninety degrees apart. An opening 138 is formed in the web portion 139 of each bracket to receive a screw 140, the lower end of which terminates in an enlarged head 141, which has a kerf therein.

A plurality of apertures 143, equal in number and in alignment with the apertures 138, is provided in the baffle member 25. Each of the apertures 143 is formed in the horizontal wall 144 of one of a series of four indentations 145, whereby a flat surface is provided for the head 141 to bear against, as seen in Fig. 6.

One of the features of the invention, as previously indicated, is the arrangement whereby the motor driven fan assembly, with its associated electrical connections, is readily removable as a unit when in need of repair, or for any other reason.

To this end, the bracket 30 is so designed that all these parts may be attached thereto, and the bottom member 22 has an opening 150 therein which is slightly larger in diameter than that

of the fan blades, so that the assembly may be inserted into or withdrawn from the housing 21 with ease.

The bracket 30 is shown detached in Fig. 12, in bottom plan in Fig. 2, and in vertical section in Fig. 5. It includes a substantially circular central body portion 152 from which three integral laterally extending arms 153 emanate, the center lines of the arms being spaced one hundred twenty degrees apart.

From the central body portion 152, each arm 153 extends angularly upwardly as at 154 to terminate in a horizontally disposed end portion 156, a depressed reinforcing rib 157 on the center line serving to strengthen each arm in this region. As shown in the drawings, the entire bracket is further strengthened by upstanding flanges 158 formed along the side margins of the arms and the body portion.

Means are provided on one of the arms 153 to mount a choke coil assembly, said assembly being designated 160.

The arm referred to being the one in line with the front standard 23 is also provided with an insulated opening 161 through which the cord 27 passes. In all other respects, the three arms 153 are identical.

To provide the support for the assembly 160, each side flange 158 of the arm aforesaid is provided intermediate the body portion 152 of the bracket and the arm end 156 with an integral upward extension 164 terminating in a horizontal laterally projecting flange 165. Each flange 165 has therein one or more apertures 166, whereby the assembly 160 may be secured thereto by screws, or the like.

With particular reference to Fig. 2 and the lower portion of Fig. 7, the means whereby the bracket 30 is detachably secured to the bottom member 22 will now be described.

Integral with said bottom member, and extending inwardly into the opening 150, are three ears 168 each provided with a pair of spaced threaded apertures 169. The end portion 156 of each arm likewise has a pair of spaced openings 170 therein in alignment with the apertures 169.

Each opening 170 is provided with a rubber bushing 171 through which a screw 172 passes, and thereafter through an aperture 169. A metal washer 174 is interposed between the head 175 of the screw and the bottom face of the bushing 171 to provide adequate bearing surface for said bushing. With this arrangement, the bracket 30 as well as the screws 172 are insulated from the housing.

The central body portion of the bracket has formed therein a plurality of upstanding hollow bosses 178, each of which has a central aperture. In the embodiment illustrated, four such bosses are shown, they being spaced ninety degrees apart.

Similarly, the casing of the motor 26 includes four bosses 180 from each of which the threaded lower end 181 of a field stud projects. Each of these projecting ends pass through one of the apertures in the bosses 178 to receive a lock washer and nut assembly 182. Thus, the motor and its associated fan assembly is securely fastened to and supported by said bracket.

The novel design of the structure described has, from a production standpoint, many advantages which have not been hereinbefore mentioned. For example, a single die is utilized to form the top and bottom cover members. The metal re-

moved from the bottom member in forming the opening 150, instead of being scrapped, is used to form the three standards 23. Also, a single die is used to form all three standards.

Assembly and operation

The construction of the present fan is of such character that it obviously can be quickly assembled and just as quickly disassembled. The steps in an assembly operation need not necessarily follow one another in the exact order set forth below. However, such procedure has been found very satisfactory in line production.

It is, of course, understood that, before the assembly operation is begun, the top member 36 will have the brackets 134 welded in place, and the standards 23 will have the stud elements 51 and 52 spot-welded thereto in proper position. Also, the bracket 30 will have the motor 26 and the assembly 160 securely attached thereto, and each cleat 109 will have a stud element 114 spot-welded thereto. The housing 21 will have the strips 92 welded thereto in proper position one hundred twenty degrees apart and will also have the trim member 41 and the bottom cover welded thereto.

In other words, the housing 21, strips 92, trim 41, and bottom cover 22 constitute a unitary structure or subassembly over the lower end of which the split trim ring 45 is slipped into place. This assembly is placed on a flat surface, such as a table, or the like, whereupon the guard assembly 34 is put in place.

Thereupon, the standards 23 are put in place, the entire assembly being permanently fastened together by means of the six speed nuts 94 and 98 pushed down, respectively, over the shank portions of the studs 51 and 52.

The baffle member 26 is next put in position, the upper ring 60 of the guard member 34 cooperating with the groove 126 to maintain the baffle in place during succeeding operations. The uprights of the guard member 34 enter the indentations 106 when the baffle is put in position, the upper ends 68 of the bars 64 terminating approximately flush with the upper edge and the bight 73 of the double bar members 65 extending above the uppermost edge of the baffle flange 104.

The cleats 109 are now installed, the studs 114 passing through the apertures 122, whereupon the speed nuts 124 are applied. This brings the horizontal flange 108 of each cleat under the adjacent bight portion 73 of a double bar member 65, and, at the same time, brings the vertical flange 110 into engagement with the legs 72 thereof.

The addition of the top cover 36 now follows. By aligning the threaded aperture 133 of one of the four brackets 134 with one of the four openings 143 in the baffle member, and thereupon inserting a screw 140, automatic alignment of the remainder is effected. Excessive tightening of the screws 140 is prevented relative the cover by the top ring 60 of the guard member, and relative the baffle member by the flanges 108.

In order to mount the fan assembly, the structure thus far assembled is now inverted with the top cover 36 resting on the table. The bracket 30 is then put in place, the fan assembly passing through the opening 150 into the interior of the housing. The screws 172 are then inserted, each passing successively through a metal washer 174, a bushing 171, and into an aperture 169. The switch 83 is mounted in place by means of the nut 86, and the control knob is attached by means of the screw 89.

As is apparent from an inspection of Fig. 2, the interior of the housing is readily accessible due to the large diameter of the opening 150 and the configuration of the bracket 30.

- 5 In operation, the fan of the present invention produces circulation of air over a wide area without creating a draft. With the frusto-conical peripheral arrangement, the air flows angularly upwardly, as well as laterally, in all directions.
 10 Noise is almost entirely eliminated, since there is no metal to metal contact between the fan assembly supporting means and the remaining structure.

The tendency of a motor to wobble, when mounted in a vertical position on a seat of rubber, or the like, is well known. In the present construction, all wobbling is eliminated by the six-point resilient support afforded the bracket 30 to which the motor is rigidly secured.

- 20 What we claim is:
 1. In a fan construction of the character described, a circular perforated housing, a bottom cover member therefor containing an opening, said opening being adapted to pass a fan assembly including a motor and fan blades, a plurality of individually removable and replaceable spaced standards to support the housing and the bottom cover member in an elevated position, a guard member also supported by said standards, a fan assembly mounted centrally of and within said housing, a baffle member mounted above said guard member, a support for the fan assembly, and means whereby said support is removably attached to the bottom cover member of said housing.

2. In a fan construction of the character described, a circular housing, an annular, flanged bottom cover member therefor, a plurality of spaced standards to support the housing, a fan assembly including a motor mounted centrally of and within said housing, a support for the fan assembly comprising a bracket including a central plate-like body portion from which a plurality of integral laterally extending arms emanate, means for rigidly attaching the motor included in the fan assembly to said support, and means whereby the support is removably secured to the bottom cover member of said housing, said means comprising a pair of screw elements each passing through aligned openings formed in the end portion of each arm of said bracket and in the bottom cover, and through a resilient bushing provided in each of the first named openings and interposed between the bottom cover and said end portion of each arm.

3. A ventilating fan including a cylindrical housing, air circulating means within and centrally of said housing comprising a motor with a vertical shaft having a plurality of fan blades secured to one end of said shaft, a bracket including a central plate-like body portion and a plurality of integral arms extending laterally therefrom, means to affix the casing of the motor to the central portion of said bracket, a bottom cover member for the housing having an opening therein, and means for removably fastening the bracket to the bottom cover member so as to electrically insulate it therefrom and permit limited relative movement thereto.
 4. A ventilating fan including a cylindrical housing, air circulating means within and centrally of said housing comprising a motor in vertical position with a plurality of fan blades secured to the projecting upper end of its shaft, a bracket including a central body portion and

a plurality of integral arms extending laterally and angularly upwardly therefrom, apertured upstanding hollow bosses on the body portion of the bracket, bosses on the motor casing each having the threaded end of a stud projecting therefrom and passing through one of said apertured bosses, means to engage said threaded ends and rigidly secure the motor to said bracket, a bottom cover member for the housing containing an opening, and means to removably secure the arms of said bracket to said cover member.

5. A ventilating fan construction of the type described, including a circular housing, a bottom cover member containing an opening, spaced standards removably secured to said housing and the bottom cover member, an annular guard assembly including a plurality of horizontally disposed members in parallel spaced relation fastened to a series of uprights, means on the uprights cooperating with means on each standard for securing the guard assembly to the latter with parts of the guard assembly extending above the upper edge of the housing, and a baffle member mounted on and supported by said guard member above the fan assembly in spaced relation thereto.

6. A ventilating fan construction of the type described, including a circular housing, a bottom cover member containing an opening, spaced standards secured to said housing and its bottom cover, an annular guard assembly including a plurality of horizontally disposed members in spaced relation fastened to a series of upright members to form a unitary structure, means to secure the latter to the standards with a portion thereof extending above the upper peripheral edge of the housing including a plurality of centrally apertured plates rigidly secured to the guard assembly, and horizontally disposed stud elements to receive a speed nut rigid with each standard adjacent the top and adjacent the middle portion thereof.

7. In the ventilating fan structure described, means to diffuse the flow of air over a wide area, said means comprising an annular shell including a frusto-conical portion merging into an arcuate marginal portion which terminates in an annular upstanding flange portion, a first series of identical indentations formed in said marginal portion at equally spaced points around its periphery, a horizontal aperture in the vertical wall of at least one of said first indentations, a second series of indentations formed in said conical portion at equally spaced points adjacent the arcuate portion of the shell, and a vertical aperture in the horizontal wall of each of said second indentations.

8. A motor support for the ventilating fan structure described, comprising a bracket having a substantially circular central body portion, three laterally extending arms spaced one hundred and twenty degrees apart integral therewith, each arm including an angularly upwardly inclined portion terminating in a horizontally disposed end portion, reinforcing flanges formed along the side margins of each arm and the body portion, a pair of spaced apertures provided with a rubber bushing in the end portion of each arm, and a plurality of upstanding hollow bosses formed in said central body portion, each boss having a vertical opening therein centrally thereof.

9. A guard member to support the baffle and top cover members of the fan structure described, consisting of an upper ring, an intermediate

ring, and a lower ring, all horizontally disposed in spaced parallel relation, a plurality of uprights including single bar and double bar members connected to each ring as by welding or otherwise, the single bar members having their upper and lower ends extending a short distance above said upper and lower rings respectively, each double bar member being of inverted U-shaped configuration with its bight portion in a plane above the upper ends and its leg portions extending downwardly to a plane beyond the lower ends of said single bars, a plate welded to the leg portions of each double bar member at a level intermediate the lower ring and the lower extremities of its legs, and a vertically elongated opening in each plate centrally thereof.

10. In a ventilating fan, a guard member, a baffle member, and means for removably attaching the latter to the guard member including a cleat member containing a vertical flange and an integral horizontal flange, a horizontally disposed stud element having a head portion and a shank portion, said head portion being welded or otherwise permanently secured to said vertical flange centrally thereof.

11. In a device of the type described, a top cover member, a bottom cover member, and connecting means between said members, said cover members being basically of the same shape and size so that they can be initially formed from the same die, said top cover member including a closed flat portion merging into an arcuate annular marginal portion which terminates in a vertical flange portion, a plurality of U-shaped brackets secured to the underside of said closed flat portion, each bracket comprising a pair of upstanding legs, the upper ends of which terminate in laterally projecting flange portions and the lower ends of which are joined by a horizontal web or bight portion having an aperture therethrough; said bottom cover member comprising a flat portion merging into an arcuate annular marginal portion which terminates in a vertical flange portion, an opening in said flat portion, a plurality of horizontally disposed ears extending inwardly into said opening, and threaded apertures in said ears.

12. In a ventilating fan; a vertically extending housing; a flanged bottom member therefor containing an opening; a fan assembly insertable through said opening and positioned within the housing; a bracket member supporting said fan assembly, said bracket member containing outwardly extending leg portions; and means comprising resilient bushings inserted in said leg portions for resiliently fastening the outer ends of the leg portions to the bottom member.

13. In a ventilating fan; a vertically extending housing; a flanged bottom member therefor containing an opening; a fan assembly insertable through said opening and positioned within the housing; a bracket member supporting said fan assembly, said bracket member containing outwardly extending leg portions removably fastened to the bottom member; and means comprising non-conductive bushings inserted in said leg portions for electrically insulating the same from the bottom member.

14. In a ventilating fan; a vertically extending housing; an annular member secured adjacent the bottom of the housing, said member including an inwardly extending flange portion; a baffle member mounted above the housing; and a flat cover member mounted on top of the baffle member, said cover member containing a down-

wardly extending flange portion; the bottom annular member and the top cover member being basically of the same shape and size so that they can be initially formed from the same die.

15. A baffle assembly for a ventilating fan, comprising a lower member including a frusto-conical shaped portion merging by reverse bends into an arcuate marginal portion terminating in an annular upstanding flange portion; a circular cover member positioned on top of the lower member and containing a downwardly extending annular flange portion which fits over the upstanding flange portion of the lower member; and means disposed inwardly of said marginal portion for removably fastening the cover member directly to the lower member. 15

16. A baffle assembly for a ventilating fan, comprising a lower member including a frusto-conical shaped portion merging by reverse bends into an arcuate marginal portion terminating in an annular upstanding flange portion; a plurality of spaced apertured indentations in the frusto-conical shaped portion inwardly of said marginal portion; a circular cover member positioned on top of the lower member and containing a downwardly extending annular flange portion which fits over the upstanding flange portion of the lower member; a plurality of brackets fastened to the underside of the cover member in alignment with said indentations in the lower member; and means extending through said indentations for engagement with the brackets for removably fastening the cover member directly to the lower member. 25

17. In a ventilating fan structure, a vertical cylindrical housing, an annular guard member disposed at the top of the housing, said guard member containing a series of spaced upwardly extending projections; a baffle member containing a frusto-conical shaped portion which merges 35

by reverse bends into an annular upstanding flange portion removably secured to said upwardly extending projections, the flange portion of the baffle member containing a series of indentations to receive the guard projections; a plurality of leg members secured to both the housing and the guard member; and a circular cover member containing a downwardly extending flange portion removably fastened directly to the baffle member, the flange portion of the cover member extending over the flange portion of the baffle member and the upwardly extending projections of the guard member to provide a finished appearance.

18. A ventilating fan, comprising a circular perforated housing; an annular bottom cover member for the housing; a plurality of spaced standards removably secured to the cover member to support the housing in an elevated position; a guard member removably secured to and supported by said standards and extending above the upper peripheral edge of the housing; and a baffle member supported by the guard member above the housing.

CARYL A. LINDBERG.
HOWARD W. ECKLES.
